(57) CLAIM

The ornamental design for a kid picnic table with umbrella and play kitchen sink, as shown and described.

DESCRIPTION

FIG. 1 is a perspective view of the kid picnic table with umbrella and play kitchen sink showing my new design; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; and, FIG. 8 is a bottom plan view thereof. The broken lines in the drawings depict portions of the kid picnic table with umbrella and play kitchen sink that form no part of the claimed design.

1 Claim, 8 Drawing Sheets
